[57] CLAIM

I claim the ornamental design for a lid rack, as shown.

DESCRIPTION

FIG. 1 is a perspective view of my lid rack;
FIG. 2 is a top plan view of my lid rack;
FIG. 3 is a side elevational view thereof taken from a position generally to the right of the image of FIG. 2;
FIG. 4 is a side elevational view taken generally from a position generally to the left of the image of FIG. 2;
FIG. 5 is a top elevational view taken generally from a position generally to the top of the image of FIG. 2;
FIG. 6 is a bottom elevational view taken generally from a position generally to the bottom of the image of FIG. 2; and,
FIG. 7 is a bottom plan view thereof.
